DEVICE FOR HANGING RADIATORS

Albert C. Sandberg, Lafayette, Ind.

Application July 12, 1933, Serial No. 680,141

2 Claims. (Cl. 248—17)

This invention relates to a device for hanging radiators.

It has been proposed to support radiators from the walls of buildings but the radiators must be specially constructed for this purpose and the securing bolts which fasten the radiators to the walls of the room must be located near that portion of the wall which is adjacent the sills of the window. Where it is desired to hang a radiator from the wall it is necessary to reinforce the walls at those points when the building is being constructed or it is necessary to remove a portion of the tiling and reinforce it after the walls have been constructed.

An object of the present invention is the provision of a hanger for radiators which is especially designed to eliminate the necessity of reinforcing the walls in which a plate is employed having a plurality of radially-disposed flanges adapted to engage the outer faces of the tubes of a radiator with a clamping bar engaging the inner and intermediate portions of the tubes which is adapted to be clamped by means of a bolt to the plate so that the plurality of flanges when in engagement with the outer walls of the tubes will maintain the radiator in a predetermined position, a cantilever hook being suspended from the plate for embracing the nipples between the tubes and forming a cantilever or bracket at the bottom of the radiator so that a slight tension stress is exerted only on the suspending means between the hook and wall plate.

A further object of the invention is the provision of a hanger for radiators in which a hook is employed for engaging the nipples between the tubes of the radiator with the hook having a cantilever effect and being connected by a rod or bar to a wall plate having projections to which a radiator is to be secured in a rigid position and because of this plate construction anchor bolts may be located at approximately any point that may be convenient to meet an easy installation of the radiator.

This invention will be best understood from a consideration of the following detailed description, in view of the accompanying drawing forming a part of the specification; nevertheless, it is to be understood that the invention is not confined to the disclosure, being susceptible of such changes and modifications which shall define no material departure from the salient features of the invention as expressed in the appended claims.

In the drawing:

Figure 1 is a transverse vertical section of a

radiator showing my hanger securing the radiator to the wall of a building,

Figure 2 is a horizontal section taken along the line 2—2 of Figure 1,

Figure 3 is a view in elevation of the anchor plate employed in this construction,

Figure 4 is a view in perspective of a cantilever hook for supporting lower portions of the radiator.

Referring more particularly to the drawing, 10 designates the wall of a building to which my improved hanger is applied showing an anchor bolt 11 located between blocks 12 forming the wall. These blocks may be formed of any material well known in the building art. It will be further seen 70 as the description proceeds that the anchor bolts, due to the particular construction of the hanger, may be placed at any convenient point required by emergency or conditions resulting from the cemented or mortar spaces between the blocks or 75 bricks of a building. The bolts may be used on wood studding in frame walls. Therefore, it is not necessary to apply the hanger bolt and likewise the hanger in some definite position. In other words, in the usual construction it may be 80 necessary to apply the anchor bolt at a point intermediate the upper and lower edges of the block shown in Fig. 1 which is located above the anchor bolt 11, while in the present construction the anchor bolt may be shifted to a point between 85 the block 12 which is below the anchor bolt shown in Fig. 1 and the next adjacent block.

An anchor or wall plate 15 has a rear flat face which engages the inner face of the wall 10 and is provided with a slot 16 of considerable length 90 which is adapted to receive the anchor bolt 11 and this plate is held in position by a nut 17 threaded onto the bolt. The plate is also provided with a pair of laterally extending spaced flanges 18 and 19 and the outer free edges 20 of these flanges neatly engage the outer edges 21 of the tubes 21 of the radiator 22 for which purpose the flanges provide a pair of bearing means.

On this plate 15, there is a plurality of bosses, two bosses 27, 28 being shown, which are located above and below the elongated slot 16, and between the laterally extending spaced flanges 18 and 19. These bosses have threaded bores of considerable depth, and their purpose is to provide a wide range of selection of position of the 105 bolts used in fastening the radiator to the wall. The tubes 21 of the radiator 22 will be drawn tight against these flanges 18 and 19 in unison, fixing the tubes 21 firmly against the flanges regardless of the position of wall plate in the radiator 110

proper, and allowing no release of contact at 18 and 19. The construction of this plate it will be readily seen will permit the location of anchor bolts in any convenient point, which means at 5 nearly any point back of a radiator eleven inches above bottom, and inside of the outer sections, and five inches below the top of the radiator to be hung.

A clamping bar 23 engages the inner edges of 10 adjacent tubes 21 and is provided with notches 24 when necessary to neatly fit the inner edges of the pipes 21. A bolt 25 engages the bar 23 and is screwed at 26 into the bore of one (27) of the bosses. The threaded passage 29 of the 15 second boss 28 would have received the bolt 25 had the condition been such that a more direct mounting could have been made there.

A bolt or rod member 30 (or some appropriate equivalent) has its upper end received within an 20 opening 31, in the flange 19 of plate 15, and through an opening 33 in a loosely mounted iron plate 32^a having the opening 33 threaded for $\frac{1}{2}$ " pipe. A nut 32 is threaded onto the upper end of the rod for supporting the rod from said flange. This rod extends downward and terminates above the lower portion of the radiator 20. The iron plate 32^a, threaded for a pipe allows the use of a half-inch pipe for rod 30 if desired. When the pipe is not employed this plate 32^a 30 with nut 32 placed on top of the plate 32^a then acts as a washer.

A cantilever hook member 35 is so formed that it will receive a nipple 36 located between the tubes 21. These nipples are provided for placing 35 the cross heads 36^a of the radiator in communication with the pipes 21. A base member 37 is provided with a rear flat face adapted to engage the wall 10. A radially disposed flange 38 of 40 matching width to the first-mentioned flanges projects inwardly from the base member and terminates adjacent the inner upper end of the hook 35 and has its free end in engagement with the inner edges of the tubes 21 and in the same vertical plane with the free edges of the flanges 18 and 19 of the plate 15, said flange 38 providing a third bearing means. The base member is provided with a vertical opening 39 which is 45 adapted to receive the lower end of the arm or rod 30 and a nut 40 threaded onto the lower end 50 of the rod is adapted to move the base member

37 and likewise the hook 35 upwardly in snug engagement with the nipple 36.

It will be seen by this construction that the flanges 18 and 19 when the bar 23 is clamped in position holds the upper portion of the radiator rigidly while the free edge of the flange 38 in connection with the cantilever hook 35 co-operates to rigidly hold the lower portion of the radiator in place. Thus a great number of contacts are had between the hanger and the radiator with a minimum of material for rigidly retaining the radiator against movement.

I claim:—

1. A radiator hanger adapted to be attached to anchorage means incorporated in the wall of a building, comprising a wall plate having a substantially mid-opening of considerable length for receiving the wall anchorage, said plate including parallel flanges functioning as a pair of bearing means, a clamping bar to bear against adjacent means of the radiator, a bolt engaging said bar, a plurality of bosses having threaded bores of considerable depth by virtue of occurring in the bosses, said bolt adapted to being screwed into the nearest bore, whereby said hanger serves 100 to position said radiator with respect to said anchorage, and a weight-carrying element depending from the lowermost one of said flanges. 95

2. A radiator hanger adapted to be attached to anchorage means incorporated in the wall of a building, comprising a wall plate having a substantially mid-opening of considerable length for receiving the wall anchorage, said plate including parallel flanges functioning as a pair of bearing means, a clamping bar to bear against adjacent 110 means of the radiator, a bolt engaging said bar, a plurality of bosses having threaded bores of considerable depth by virtue of occurring in the bosses, said bolt adapted to being screwed into the nearest bore, whereby said hanger serves to 115 position said radiator with respect to said anchorage, and a weight-carrying element depending from the lowermost one of said flanges, said weight-carrying element comprising a bolt member 120 and a hook member, said hook member being provided with a flange of matching width to the first mentioned flanges to provide a third bearing means between the radiator and the wall. 125
